UNITED STATES PATENT OFFICE.

HARRY K. MULFORD, OF PHILADELPHIA, PENNSYLVANIA.

VACCINE-POINT.

SPECIFICATION forming part of Letters Patent No. 758,597, dated April 26, 1904.

Application filed April 16, 1902. Serial No. 103,173. (No model.)

To all whom it may concern:

Be it known that I, HARRY K. MULFORD, a citizen of the United States, residing in Philadelphia, Pennsylvania, have invented certain

5 Improvements in Vaccine-Points, of which the following is a specification.

My invention consists of certain improvements in vaccinating instruments, having for its object the provision of an improved vaccine-point and containing vessel therefor of such a nature that they may be perfectly sterilized and which, moreover, may be put together and sealed in such a manner as to insure that each point and its capsule shall 15 be absolutely aseptic, it being, moreover, maintained for any desired period free from any possible contamination by pathogenic or other bacteria. This object I attain as hereinafter set forth, reference being had to the 20 accompanying drawings, in which—

Figure 1 is a perspective view of my improved vaccine-point, showing it as inserted in my preferred form of containing-capsule, and Fig. 2 is a perspective view of the point 25 itself.

In the above drawings, A is a preferably flattened and somewhat elongated capsule of glass, open at one end, and B is an improved vaccine-point. This latter preferably consists of a flattened glass rod, upon which is formed a point, as shown at b, by any suitable means, preferably by heating it in a blow-pipe-flame and drawing it out to a thin sharp end. The surface of the rod is etched or 35 roughened either by hydrofluoric acid, by a sand-blast, or any other desired method. In assembling these two parts of my improved device a small quantity of vaccine virus is placed in the bottom of the glass capsule A, 40 this capsule having been previously sterilized.

The roughened glass rod B is then placed within the capsule, as shown at Fig. 1, and melted paraffin placed, as at C, around the top of the capsule and between its upper edges 45 and the rod B, thus sealing the said rod within the same. The paraffin is preferably applied by means of a camel's-hair brush and quickly hardens, so as to exclude the air from the interior of the capsule.

50 It will be understood that I do not confine

myself solely to the use of paraffin for sealing the glass rod in position, as such substances as sanadrac, shellac, or other gums may also be advantageously employed.

My object in roughening the glass rod is for 55 the purpose of retaining the glycerinized virus in one position within the capsule, for on account of the irregular rough surface of the rod this latter has a comparatively high capillary attraction for the liquid, there being 60 therefore little if any tendency for the virus to change its position from the bottom of the capsule even when this is inverted. The roughened surface is also of material value 65 in providing means to which the sealing material may hold, such construction having been found to be a decided improvement over the polished or smooth surface usually formed on the ivory points previously employed.

It is further to be noted that by the use of 70 glass for the scarifying-point I am enabled to perfectly sterilize the same, since it is not in any way attacked by any of the processes of sterilization at present practiced. This cannot be said of the points of ivory, bone, or 75 quill heretofore used, since these being always more or less porous and composed of animal matter cannot be completely sterilized nor treated in a manner similar to that in which mineral substances could be operated upon 80 without injury.

It will thus be seen that by my improved device the vaccine virus is contained within a package which may be made absolutely aseptic and one which is, moreover, substantial and 85 so constituted that it cannot in any way deteriorate or be easily injured by transportation or handling.

I claim as my invention—

1. As a new article of manufacture, a vaccine-point having a surface etched so that it will be wet by a liquid, substantially as and for the purposes set forth.

2. As a new article of manufacture, a scarifying-point composed of a mineral substance 95 having a portion of its surface etched so that it will be wet by a liquid, and a capsule also composed of a mineral substance and open only at one end, for receiving one end of said scarifying-point, with aseptic sealing material 100.

between the capsule and the body of the scari-
fying-point, substantially as described.

3. In combination with a vaccine-point, a
shell of the character described formed of glass
5 tubing flattened throughout its extent and
open at one end only, said shell being hermet-
ically closed at all points save its open end,
the outer end and the greater part of the un-
treated portion of the vaccine-point being in-
10 closed by the shell, with sealing material in-
serted in the open end of the shell and around
the untreated portion of the point, substan-
tially as described.

4. In combination with a vaccine-point, a
15 shell of the character described formed of glass
tubing flattened throughout its extent and
open at one end only, said shell being hermet-
ically closed at all points save its open end,
the outer end and the greater portion of the
20 untreated portion of the vaccine-point being
inclosed by the shell, with a sealing material in-
serted in the open end of the shell and around
the untreated portion of the point, substan-
tially as described.

25 5. In combination with a glass vaccine-point,
a shell of the character described formed of
glass tubing and open at one end only, said

shell being hermetically closed at all points
save at its open end, the outer end and the
greater part of the untreated portion of the 30
glass vaccine-point being inclosed by the shell,
with a sealing material inserted in the open
end of the shell and around the untreated por-
tion of the point, substantially as described.

6. In combination with a vaccine-point, a
shell of the character described, of a length
slightly less than said point formed of glass
tubing flattened throughout its extent and
open at one end only, said shell being tapered
40 at its closed end and hermetically closed at all
points save its open end, the treated end and
the greater part of the untreated portion of
the vaccine-point being inclosed by the shell
and a sealing material inserted in the open end
45 of the shell and around the untreated portion
of the point, substantially as and for the pur-
pose described.

In testimony whereof I have signed my name
to this specification in the presence of two sub-
scribing witnesses.

HARRY K. MULFORD.
